UNITED STATES PATENT OFFICE

128,522

DESIGN FOR A COMBINED SLIP AND ARM SHIELDS

Jeannette Chasanoff, Brooklyn, N. Y.

Application April 24, 1941, Serial No. 100,598

Term of patent 7 years

To all whom it may concern:

Be it known that I, Jeannette Chasanoff, a citizen of the United States and a resident of Brooklyn, New York, in the county of Kings and State of New York, have invented a new, original, and ornamental Design for a Combined Slip and Arm Shields, of which the following is a specification, reference being had to the accompanying drawing, forming part thereof, wherein—

Fig. 1 is a front view of a combined slip and arm shields showing my new design.

Fig. 2 is a side view thereof; and

Fig. 3 is a rear view thereof.

I claim:

The ornamental design for a combined slip and arm shields, as shown.

JEANNETTE CHASANOFF.
